US00D922349S

(12) **United States Design Patent** (10) **Patent No.:** **US D922,349 S**
Pedersen (45) **Date of Patent:** **** Jun. 15, 2021**

(54) **HEADSET FOR TELEPHONE AND COMMUNICATION EQUIPMENT**

(71) Applicant: **GN AUDIO A/S**, Ballerup (DK)

(72) Inventor: **Rasmus Trudslev Pedersen**, Ballerup (DK)

(73) Assignee: **GN AUDIO A/S**, Ballerup (DK)

(**) Term: **15 Years**

(21) Appl. No.: **29/732,341**

(22) Filed: **Apr. 23, 2020**

Related U.S. Application Data

(62) Division of application No. 29/670,994, filed on Nov. 21, 2018, now Pat. No. Des. 898,711.

CLAIM

The ornamental design for a headset for telephone and communication equipment, as shown and described.

DESCRIPTION

FIG. 1 is a front plan view of the headset for telephone and communication equipment.

FIG. 2 is bottom plan view of FIG. 1 thereof.

FIG. 3 is a top plan view of FIG. 1 thereof; the broken lines on the earpiece cushions represent the bounds of the claimed design;

FIG. 4 is a right side plan view of FIG. 1 thereof.

FIG. 5 is a left side plan view of FIG. 1 thereof.

FIG. 6 is a rear plan view of FIG. 1 thereof; and,

FIG. 7 is a top perspective view of FIG. 1 thereof.

The features shown in broken lines depict environmental subject matter only and form no part of the claimed design.

1 Claim, 7 Drawing Sheets
